UNITED STATES PATENT OFFICE

JOHN WEST, OF WEST DIDSBURY, ENGLAND.

MACHINE FOR CHARGING AND DRAWING GAS-RETORTS.

No. 845,834.

Specification of Letters Patent.

Patented March 5, 1907.

Application filed August 18, 1902. Serial No. 120,133.

To all whom it may concern:

Be it known that I, JOHN WEST, a subject of the King of Great Britain and Ireland, whose residence and post-office address is 5 Barfield House, West Didsbury, near Manchester, in the county of Lancaster, England, have invented certain new and useful Improvements in Machines for Charging and Drawing Gas-Retorts; and I do hereby declare the following to be a full, clear, and exact description of the invention, such as will enable others skilled in the art to which it appertains to make and use the same.

My invention relates to improvements in 15 apparatus for charging and drawing gas-retorts—*i. e.*, for charging the retorts with coal and drawing the coke product therefrom after the coal has been carbonized.

The object of my invention is the production of a self-propelled machine in which the operations of charging and drawing are accomplished by mechanism operable by one set of gearing.

A further object is to so position the operating levers of said machine that they are accessible to the operator at all times without changing his position.

Other objects are the provision of charging and drawing mechanism adapted to be raised or lowered at will to operate in retorts positioned at different heights and to provide hoisting mechanism to accomplish this object; to provide novel means for tilting and manipulating the drawing mechanism at will, so that it can be made to pass over the coke when entering the retort and lowered to engage and draw the coke, and to provide improved mechanism for operating the charging and drawing devices and novel means for automatically tilting the charging-scoop.

To accomplish these objects, my invention consists in the novel construction and arrangement of parts hereinafter more specifically described, reference being had to the accompanying drawings, in which—

Figures 1 and 2 are opposite views of the combined charging and drawing machine. Figs. 3 and 4 are respectively a front elevation and plan view of the same adapted for carrying a double-scoop charger. Fig. 5 is a side view of a modified form of combined charging and drawing machine adapted for carrying a single-scoop charger. Fig. 6 is a front elevation of the same.

Referring to said drawings, and particularly to Figs. 1, 2, 3, and 4, the apparatus

comprises the upright frames *a a a* and *b b b*, which are secured in any suitable manner to the truck 1 of the machine, which is mounted on wheels 2 and is adapted to be 60 propelled on ways or rails 3 along the bench of retorts 4 by means of a motor 5, which may be driven by steam, compressed air, or electrical energy, the said motor being provided with suitable reversing mechanism or 65 gear to admit of its being operated in either direction. The said motor is provided with a driving-shaft 6, on which is mounted a worm (not shown) which communicates motion through a worm-wheel 8 to the vertically-disposed shaft 9, on which said worm-wheel 8 is mounted, the said shaft being supported in bearings 9', which are secured to the upright *a* of the machine. The said shaft 9 is provided with or has mounted 70 thereon clutches 10 and 11, which are operated by means of the lever 12, the lower end of which is connected to one end of the connecting-rod 13, the opposite end of which rod is connected to the counterweighted lever 14, which is connected to and actuates said clutch 10. A vertically-disposed connecting-rod 15 is connected at the lower end to one of the members of said lever 14 and at the upper end to the lever 16, which is 75 connected with and actuates clutch 11. When lever 12 is in the position shown in Figs. 1 and 2, clutch 10 is thrown into engagement with clutch 17, which is integrally connected with the bevel-wheel 18, which is 80 normally loose on shaft 9, thereby rigidly securing said wheel 18 on said shaft 9, and thus transmitting power from the motor through the worm-gear, heretofore described, and said wheel 18 to the bevel-wheel 19, 85 mounted on the axle 20 of the machine in mesh therewith, for the purpose of propelling the machine along the bench of retorts. When the hand-lever 12 is thrown in an opposite position to that shown in Figs. 1 and 2, clutches 10 and 17 are disengaged, and simultaneously therewith the lever 16 throws the clutch 11 into engagement with clutch 21 on the lower end of the shaft 22, and power is then transmitted from the motor to 90 said shaft 22. The said shaft 22 is supported in bearings formed in the bracket 23, which is secured to the frame *a* of the machine and has mounted thereon at or near the upper end thereof the double clutch 24, which is 95 adapted to be actuated by the counterweighted lever 25, connected to the hand-lever 100

adapted to be actuated by the counterweighted lever 25, connected to the hand-lever 105

26 by means of the connecting-rod 27. When the hand-lever 26 is thrown in a direction to the left in Fig. 2, the counterweighted lever 25 causes the lower clutch member of the double clutch 24 to engage a clutch member 28', integral with the bevel-wheel 28, normally loose on shaft 22, thereby rigidly securing said wheel 28 on said shaft and transmitting power to the shaft 29 through the bevel-wheel 30, mounted on one end of said shaft 29. A bevel-wheel 31 is mounted on the opposite end of said shaft 29, which meshes with and transmits power to a similar bevel-wheel 32, which is mounted on one end of shaft 33, which extends at right angles to said shaft 29 and to a pair of chain-drums 34 and 35, mounted on said shaft 33. The said drums are so secured on said shaft that they may be disconnected therefrom for the purpose of enabling either of them to be revolved in opposite directions by hand when it is necessary to take up or pay out the chain to suit the height of the charger from the ground line. A chain 36 is led from this drum 35 under pulley 37, around pulley 38, mounted on one end of the charger-frame, thence to opposite end of said frame, and is fastened to pulley 39 for the purpose of drawing or advancing the charger into the retort when said chain-drums are operated, and a chain 40 is also led from said drum 34 under pulley 41 to the opposite end of said charger-frame and passes around pulleys 42 43 and is fastened to pulley 44 for the purpose of withdrawing the charger from the retort after the retort is charged with coal.

A double-scoop charger 45, having a shaft 46, with gearing for reversing the scoop carried by the carriage 47, is supported by a frame provided with sides 48, 48, suspended from the coal-hopper 49, which is provided with a feeder-box, in which is feed mechanism 50, comprising a worm-gear driven by the hand-wheel or the levers 51, 52 for the purpose of supplying the charger with coal. The mechanism for reversing the scoop comprises the gear-wheel 53, mounted on the shaft 53', on which the chain-pulleys 39 and 44 are mounted, which meshes with the wheel 54 on shaft 55, on which a bevel-wheel 56 is also mounted, through which motion is transmitted to the shaft 46 the end of which is provided with a bevel-wheel 57 to admit of this. The carriage is carried, as heretofore described, through the medium of the gearing driving the chain 36 until the pawl mechanism 58 on the carriage, as shown in Fig. 1, engages the rack 59. When the forward movement of the carriage is at its limit and is arrested, continued pull on the chain 36 turns the scoop through the medium of its gearing mounted in said carriage. On the reverse movement of the carriage through chain 40 the pawl trips the ratchet, and when the carriage arrives at the position shown in Fig. 4

the continued pull on chain 40 operates wheel 44 to restore the scoop to normal position to receive coal.

The operator by disengaging the lower clutch member of the double clutch 24 from the clutch member 28', integral with the bevel-wheel 28, arrests the transmission of power to the gearing for driving the charger into and withdrawing the same from the retorts and may then, by actuating the hand-lever 26 in an opposite direction, throw the upper clutch member of the double clutch 24 into engagement with a clutch 60 on the gear-wheel 61, normally loosely mounted on the extreme upper end of shaft 22, thereby rigidly securing said wheel 61 to said shaft 22 and transmitting power to a gear-wheel 62, mounted on the lower end of shaft 65, and to a worm 64. The said worm 64 is mounted on shaft 65, Fig. 3, and meshes with and transmits power to a worm-wheel 66, mounted on the shaft 67, on which are also mounted the chain-drums 68, 69, and 70. The chains 71 and 72 are led from said drums respectively to and around pulleys 73, attached to the hopper 49 and to the framing. When power transmitted as described is applied, the hopper 49 and charger 45 is elevated or lowered to the height required.

A chain 75, leading from the drum 70, is led around pulleys 77 and 78 (see Fig. 3) and fastened at one end to a pulley 79, which is keyed to a shaft 80, on the opposite end of which is mounted the worm-wheel 81, which meshes with and transmits power to a worm 82, mounted on the upper end of the shaft 83, which is adapted to be operated by the hand-wheel 84, as shown in Figs. 3 and 4. The chain 75, leading from the drum 70, is for the purpose of elevating and lowering the rake-bar frame to the height required for the retort to be drawn, and the hand-wheel 84, with the worm-gearing 82 and 81, is for the purpose of adjusting the length of chain without putting in motion the chains 71 and 72, leading over the drums 68 and 69 to the hopper 49. The chain-pulley 78 is attached to the rake-bar frame 85, which supports the rake-bar 86, which is provided with chains 87 and 88, leading around pulleys 89, 90, 91, 92 to chain-drums 93, mounted on the shaft 94, on one end of which is also mounted the pinion 95, which is engaged and adapted to be driven by a rack 96, which is connected to the piston-rod 97 of the cylinder 98. The said cylinder 98 is provided with a valve-casing 99, in which a suitable valve is located which is operated by the hand-lever 100 through the medium of the connecting-rod 101, whereby compressed air or other motive fluid is admitted to either side of the piston in said cylinder.

The rake-head 106, which is attached to the rake-bar, is driven into and withdrawn from the retorts through the action of the

rack and the chain-gearing described, and the frame 85, which is pivoted, is caused to rock thereon by means of the hand-lever 107, which is connected to the vertically-disposed rod 108, which is adapted to be clamped to said frame by means of the wrenches 109 110. This action imparts the necessary motion for raising the rake-head when it passes into the retort over the coke and lowers the head into the coke when the rake is being withdrawn.

It will be seen that all the levers for directing the various operations are placed in positions readily accessible to the operator when standing on the platform 111.

In Figs. 5 and 6 I show a modified form of my invention applied to a single scoop-charger and carriage, which necessitates a longer coal-hopper 74' and alteration in the arrangement of the axle-wheels and base of the double-scoop machine heretofore herein described and illustrated in Figs. 1, 2, 3, and 4 of the drawings. A separate or independent motor or cylinder is employed for the purpose of driving the charger into and withdrawing the same from the retorts. In the apparatus illustrated in Figs. 5 and 6 the frames *a*, *b* are secured upon the truck *c*, which is mounted on two pairs of wheels *c'*, *c''*, which are adapted to travel on rails in a manner identical to that heretofore described. A motor *e'*, mounted on the truck and similar in construction to that heretofore described, is adapted to transmit power through its shaft *e''* and a worm (not shown) mounted thereon to the worm-wheel *e'*. A clutch *e*, mounted on a vertical shaft, is adapted to be thrown into engagement at the will of the operator with either the clutch member *e*¹⁰, integral with the bevel-wheel *e*¹¹, or the clutch member *e*¹², integral with the bevel-wheel *e*¹³, by actuating the hand-lever *e*¹⁴, which is connected to said clutch by means of the connecting-rod *e*¹⁵ and the lever *e*¹⁶. When said clutch *e* engages the clutch member *e*¹² of the wheel *e*¹³, which is normally loose on the vertical shaft, the said wheel is made part of them, and power is transmitted to the bevel-wheel *e*¹⁴, fast on the axle, with which it meshes for the purpose of propelling the machine along the bench of retorts. When, however, the clutch is in engagement with the clutch member of the bevel-wheel *e*¹¹, also normally loose on said shaft *e*⁸, the said wheel is fastened on said shaft and power is transmitted therethrough to the bevel-wheel *e*¹⁷, mounted on the shaft *e*¹⁸, with which it meshes to the chain-drums *e*¹⁹ and *e*²⁰, mounted on the shaft *e*²¹, by means of a worm on shaft *e*¹⁸ (not shown) and a worm-wheel on shaft *e*²¹ (not shown) for the purpose of actuating the hoisting-chains *e*²² and *e*²³, respectively, driven thereby. The said chain *e*²² is led over pulleys *e*²⁴, *e*²⁵, *e*²⁶, mounted in the upper frame, and chain *e*²³ is led over pulleys

*e*²⁷, *e*²⁸, *e*²⁹, mounted on the hopper 30, and are finally anchored to the top of the frame, as shown in Fig. 6. The hoisting-cable *e*³⁰ of the rake-bar frame is wound on said chain-drum *e*²⁰ and led over pulleys *e*³¹, *e*³² to the rake-frame *e*³³, to which it is attached at *e*³⁴, as shown in Fig. 6. When the hoisting-gear is put into motion, the chains *e*³⁰, *e*²², and *e*²³ simultaneously raise or lower the hopper 74', the charger-scoop 45, and the rake-bar 86, 75 Figs. 1-4, to the position required for charging and drawing the retorts. In the machine illustrated in Figs. 5 and 6 the cylinder *e*³⁵, with its valve casing or box *e*³⁶, is preferably secured to the framework supporting the coal-hopper 74. In other respects it is similar to that illustrated in Figs. 1, 2, 3, and 4, heretofore described. The movements of the piston *e*³⁷ of said cylinder are controlled by the hand-lever *e*³⁸ through the connections *e*³⁹, *e*⁴⁰, *e*⁴¹, *e*⁴², and *e*⁴³. The said piston is attached to or connected with the rack *e*⁴⁴, which meshes with and operates a pinion *e*⁴⁵, which is mounted on the end of shaft *e*⁴⁶, on which is also mounted the chain-drum *e*⁴⁷, over which the chains *e*⁴⁸ and *e*⁴⁹ pass. The said chains pass from said drum onto and over, respectively, pulleys *e*⁵⁰ and *e*⁵¹, mounted in the rake-bar frame, the said chains being for the purpose of driving the rake into and withdrawing the same from the retorts. The rake is pivoted and rocks therein by the lever *e*⁵² and the rod *e*⁵³, as heretofore described. The charger is driven into and withdrawn from the retorts by means of the motor *e*⁵⁴, which comprises the cylinder *e*⁵⁵, in which the piston *e*⁵⁶ is adapted to operate. The said piston is connected with a rack *e*⁵⁷, which engages and transmits power to a pinion *e*⁵⁸ on the shaft *e*⁵⁹ for the purpose of operating the chain-drum *e*⁶⁰, mounted on said shaft. The said piston carries the cross-head *e*⁶¹, on which a tappet *e*⁶² is secured. The said piston in its movements causes the said tappet to contact with the tappet-lever *e*⁶³, which is pivotally connected with and adapted to actuate the vertically-disposed rod *e*⁶⁴, (shown in dotted lines in Fig. 5,) which operates the valve-rod *e*⁶⁵ for the purpose of controlling the admission of motive fluid through the valve-casing *e*⁶⁶ to the cylinder at each backward-and-forward movement of the said piston. Chains (not shown) pass over the chain-drum *e*⁶⁰ and are attached to the ends, respectively, of the charger for the purpose of advancing the same into and withdrawing it from the retorts. The vessel *e*⁶⁷ is for the purpose of containing water when the apparatus is actuated by hydraulic pressure, and the rods in dotted lines in Fig. 5 show a valve-actuating mechanism to control the admission of water from said vessel to the motor *e*⁵⁴. As it does not relate directly to the present invention, I will not further describe the same. The

motors e^{54} and e^{55} and the cylinder e^{35} is actuated by air or steam admitted thereto from the main supply-pipe e^{88} through, respectively, the pipe e^{64} , the casing e^{70} , in which a control-valve is located, adapted to be actuated by the valve-rod e^{71} , which is shown in Fig. 5 to be connected to the clutch-lever mechanism, and the pipe e^{72} , the pipe e^{73} , and the pipe e^{74} .

10 Having now described the mechanism of the machine, I will describe the operation of drawing and charging a retort which has been previously charged with coal which has been carbonized and its coke is ready to be drawn from the retort.

Having raised or lowered the coal-hopper and the charger and the rake-head by means of the motor and gear to the level of the retort to be drawn and charged, the machine 20 is propelled by the traveling gear until the rake-head is opposite the retort to be drawn. The attendant then by means of the hand-lever 100, Figs. 1-4, or e^{88} , Figs. 5, 6, directs the compressed air or steam into the cylinder 25 98, Figs. 1-4, or e^{35} , Figs. 5, 6, on the lower side of the piston therein, causing the rack to move upward and the rake to enter the retort, when after it has traveled sufficiently over the coke the hand-lever is reversed 30 and the rake-head is withdrawn, bringing the coke out of the retort. During the operation of sending the rake-head into the retort the head is raised by the lever 107, Figs. 1-4, or e^{82} , Figs. 5, 6, to enable it to go over 35 the coke in entering the retort, and when the rake-head is being withdrawn the said lever is moved in an opposite direction and the head is depressed into the coke. This operation is repeated until the whole of the coke 40 is withdrawn from the retort, when the machine is moved until the charger is opposite the retort, when the charger is filled with coal from the coal-hopper, and by means of the motor 5 and the gear connected with it in the 45 machine having a double charger or with the cylinder e^{54} in the machine having a single scoop-charger the charger is sent into the retort and its contents deposited in the retort. This operation being performed, the 50 machine is traveled to another retort, to be drawn and charged.

What I claim, and desire to secure by Letters Patent, is—

1. A combined charging and drawing machine, comprising a frame, a trackway or guide-frame adjustable up and down to different desired heights on the main frame, to position it opposite the retort to be charged, a charging-scoop adapted to travel to and fro on said adjustable trackway, another trackway-frame adjustable up and down to different desired heights on the main frame aforesaid to position it opposite the retort to be drawn, a rake adapted to travel to and 65 fro on said last-mentioned adjustable track-

way, means for traveling the scoop to and fro on its trackway, means for traveling the rake to and fro on its trackway, and a single operating means carried by the main frame of the machine for adjusting the respective trackways up and down to desired positions opposite the retorts. 70

2. A combined charging and drawing machine comprising a frame, a trackway or guide-frame adjustable up and down to different desired heights on the main frame to position it opposite the retort to be charged, a charging-scoop adapted to travel to and fro on said adjustable trackway, another trackway-frame adjustable up and down to 80 different desired heights on the main frame aforesaid to position it opposite the retort to be drawn, a rake adapted to travel to and fro on said last-mentioned adjustable trackway, means for traveling the scoop to and fro on its trackway, means for traveling the rake to and fro on its trackway, and a single operating means for adjusting the respective trackways simultaneously up and down on the main frame to thereby position the scoop and 90 the rake carried by said trackways at the same height for operation in the retorts. 95

3. In a machine of the class described, the combination with a main frame or carriage, of a motor carried thereby, said motor having a power-shaft, propelling traction-wheels for the main frame, an operating-shaft, clutch mechanism for coupling the power-shaft of the motor either to the propelling-wheels or to the operating-shaft at will, charging mechanism, hoisting means driven by said operating-shaft for adjusting the charging mechanism to different heights to operate in retorts of different heights, means for operating the charging mechanism to charge the retort, drawing mechanism adjustable to different heights to operate in retorts of different heights, hoisting mechanism driven by said operating-shaft for raising and lowering the drawing mechanism at the 105 same time with the charging mechanism, and means for coupling or uncoupling the operating-shaft to the charging and drawing mechanisms. 110

4. In a machine of the class described, the combination with the machine-frame, of charging mechanism and drawing mechanism both carried by said frame and both adapted for positioning at different heights to operate in retorts at different heights, drum-and-cable hoisting mechanism mounted on the same machine-frame aforesaid for raising and lowering the charging and drawing mechanisms simultaneously and equally, and means for operating said drum-and-cable hoisting mechanism from a single source of power to raise or lower said charging and drawing mechanisms simultaneously and equally. 120 125

5. In a machine of the class described, the combination with the machine-frame, of 130

charging and drawing mechanism both carried by said frame and both adapted for positioning at different heights to operate in retorts at different heights, hoisting-drums 5 mounted on the same machine-frame aforesaid, independent cables winding on said drums and connected, respectively, to the charging and drawing mechanisms, and means for driving said drums simultaneously 10 from a single source of power to raise and lower the charging and drawing mechanisms simultaneously and equally.

6. In a machine of the class described, a machine-frame, a device for manipulating 15 the material, said device being adapted for positioning at different heights to operate in retorts at different heights, a hoisting-drum, a cable operated by said drum for raising and lowering the material-manipulating device, 20 and independent means for taking up a desired length of the cable without necessitating operation of the hoisting-drum.

7. In a machine of the class described, a machine-frame, a device for manipulating 25 the material, said device being adapted for positioning at different heights to operate in retorts at different heights, a hoisting-drum, a cable operated by said drum for raising and lowering the material-manipulating device, a 30 pulley to which the cable is fastened, and means for operating and locking the pulley at will to take up a desired length of the cable without necessitating operation of the hoisting-drum.

35 8. In a machine of the class described, the combination with a machine-frame, of a

charging device, hoisting-drums and cables for raising and lowering said charging device to different heights to position it opposite the desired retort, independent drum-and-cable 40 means for operating the charging device back and forth to charge the retort, a motor, an operating-shaft turned by said motor, and clutch mechanism for coupling either the hoisting-drums to the operating-shaft or 45 coupling the charging-mechanism-operating drum to the operating-shaft.

9. In a machine of the class described, the combination with a machine-frame, of independent charging and drawing devices, drum-and-cable means for raising and lowering the charging and drawing devices to position them at the desired heights for operation in the retorts, independent drum-and-cable 50 mechanism for operating the charging device back and forth, independent drum-and-cable mechanism for operating the drawing device back and forth, independent means for operating the drum-and-cable means of the drawing device, a motor, an operating-shaft 55 turned by said motor, and clutch mechanism for coupling either the charging-device-operating drum to the operating-shaft or for coupling the hoisting-drums of both the charging and drawing devices to said operating-shaft.

In testimony whereof I have affixed my signature in presence of two witnesses.

JOHN WEST.
